INVENTOR

James E. McIntire

UNITED STATES PATENT OFFICE.

JAMES E. MCINTIRE, OF WEYMOUTH, MASSACHUSETTS, ASSIGNOR TO P. R. GLASS COMPANY, OF BOSTON, MASSACHUSETTS, A CORPORATION OF MASSACHUSETTS.

FOLDING-MACHINE.

1,278,490.

Specification of Letters Patent. Patented Sept. 10, 1918.

Application filed February 7, 1916. Serial No. 76,666.

To all whom it may concern:

Be it known that I, JAMES E. MCINTIRE, a citizen of the United States, residing at Weymouth, in the county of Norfolk and 5 State of Massachusetts, have invented certain Improvements in Folding-Machines, of which the following description, in connection with the accompanying drawings, is a specification, like reference characters on 10 the drawings indicating like parts in the several figures.

This invention relates to folding machines and is herein illustrated in connection with a machine for folding a binding strip over 15 the edge of a piece of upper material for use in the manufacture of boots and shoes.

For convenience of description the upper material will be referred to as a piece of leather and the binding as a strip of fabric. 20 It is customary in the manufacture of certain styles of shoes to stitch to a piece of the upper, for example a vamp, a strip of fabric, apply cement to said fabric and then fold the fabric over the leather to form a 25 binding. Hitherto the folding has been done by hand; and the general object of the present invention is to provide mechanism for performing this folding operation.

According to one feature of the invention 30 a gage extends into the junction of the leather or other material with the binding at a point at which the work is unfolded. There is thus provided proper means for guiding the work as it is fed to the folding 35 mechanism.

This and other features of the invention, including certain details of construction and combinations of parts will be described in connection with an illustrative machine and 40 pointed out in the appended claims.

Referring to the accompanying drawings,—

Figure 1 is a perspective of a portion of a machine in which the present invention is 45 embodied, showing a piece of work in process of being folded;

Fig. 2 is a detail perspective on an enlarged scale of the folding and pressing instrumentalities;

50 Fig. 3 is a perspective of the effective end of the edge gage and the preliminary turning member;

Fig. 4 is a perspective of a piece of leather

to which a fabric binding strip has been stitched, and 55

Fig. 5 is a similar view showing the binding turned back ready to be folded.

The invention has been illustrated in connection with a machine of the type shown and described in British Patent No. 19,937 60 of 1914. In the illustrative machine, as in the machine of the patent, the work 100 is fed intermittently over a support 1, and the margin of the work is progressively folded over the end of a creaser 3 by a folder or 65 folding finger 5 which is continuously reciprocated to turn the margin of the work progressively over the end of the creaser after the manner shown in Figs. 1 and 2. The oscillating presser or hammer 7 acts 70 to press the fold as indicated in Fig. 2, and serves also, in connection with a movable anvil (not shown) to feed the work. The movement of the presser is as follows: Starting with the raised position shown in 75 Fig. 1, it descends to the position shown in Fig. 2 in which it presses the folded margin upon the anvil. The hammer and anvil then move in unison to the left as viewed in Fig. 2 to feed the work, after which the 80 hammer rises and then both hammer and anvil return to the starting position. In order to facilitate the feeding of the work, the hammer or presser 7 has fastened to it a resilient finger 10 the operative end of 85 which extends toward the creaser 3 and engages the work at a point removed from the edge thereof. As thus far described, the illustrative machine is substantially identical with that of the British patent and no 90 further detailed description of it will be given.

The machine of the patent is adapted to fold the skived margin of a piece of leather. In the present case, however, the leather is 95 neither skived nor folded. Referring to Fig. 4, there is shown a portion of a shoe upper, for example a quarter, to which has been stitched at 9 a strip of fabric 11 which is later to serve as a binding for the edge 100 of the leather. After having been stitched in place the binding is cemented and turned back into the position shown in Fig. 5. The leather part with the cemented binding is then placed upon the support 1 (see Fig. 105 1) with the cemented side of the binding

uppermost and presented to the feeding and folding mechanism. In order to guide the work a gage 13 pivoted at 15 to a stationary part is normally pressed down upon the flat 5 top of a preliminary turning member 17 by a spring 19 and is provided at its rear end with a flat projection 113 pressure upon which by a finger of the operator will raise the operative end of the gage to permit presentation 10 of the work. The operative end 213 of the gage extends downwardly into the corner formed at the junction of the leather with the fabric and engages the edge of the leather thereby serving to guide the 15 work as it is fed. Although in the illustrative machine a preliminary turning member is shown the turning function of this member is not essential, its principal function being to receive on its flat top the stem 20 of the edge gage 13 and thereby to prevent the operative end 113 of said gage from pressing with any considerable force upon the binding.

Although the invention has been set forth 25 in connection with a machine having a movable folder, a stationary creaser, and a combined feeding and fold pressing mechanism, it should be understood that this has been done to promote brevity and clearness and 30 that the invention is not limited in the scope of its application to the particular type of machine shown and described.

Having thus described my invention, I 35 claim as new and desire to secure by Letters Patent of the United States:

1. A machine for folding a piece of work which consists of a piece of material to 40 which a strip of binding has been attached throughout its length having, in combination, means for feeding the work, a gage arranged to engage an unfolded portion of the work at a distance from the edge thereof, and means located entirely in the rear of the gage for folding the binding over 45 the edge of the material.

2. A machine for folding a piece of work which consists of a piece of material to 50 which a strip of binding has been attached throughout its length, having, in combination, means for feeding the work, a gage arranged to extend into the corner at the junction of the material with the binding at a point at which the work is unfolded, and means for folding the binding about the 55 edge of the material.

3. A machine for folding a piece of work which consists of a piece of material to 60 which a strip of binding has been attached throughout its length, having, in combination, a gage arranged to extend into the corner formed by the attachment of the

binding to the material, and means for folding the binding about the edge of the material.

4. A machine for operating upon a piece 65 of work which consists of a piece of material to which a strip of binding is attached having, in combination, means for feeding the work intermittently into position to be operated upon, an edge gage arranged to extend into the corner at the junction of the material and the binding, a creaser the operative portion of which is located close to the edge of the material, a folder for turning the binding over the creaser, and a 70 presser to press the binding upon the material.

5. A machine for operating upon a piece 75 of work which consists of a body material to which a more flexible strip has been attached throughout its length, said material and strip being so related that at their juncture the edge of the material forms a shoulder, comprising means for guiding the work by engagement with the shoulder at 80 an unfolded portion of the work, and means for progressively folding the strip over the material.

6. A machine for folding over the edge 85 of a piece of leather a piece of fabric which 90 is attached to the margin of said leather, having, in combination, means for feeding the work intermittently into position to be operated upon, an edge gage extending over the unfolded fabric and into engagement 95 with the edge of the leather, and folding and pressing mechanisms located in the rear of said edge gage.

7. A machine for folding over the edge 100 of a piece of leather a piece of fabric which has been attached throughout its length to the margin of said leather, having, in combination, an edge gage extending over the unfolded fabric into engagement with the edge of the leather, means for feeding the 105 work past the gage, and means for folding the fabric over the leather and pressing it into place.

8. Mechanism for feeding and guiding a 110 piece of work which consists of a piece of material to which a second piece of material has been attached throughout its length, comprising a bed for supporting the work, a gage arranged to extend into the corner at the junction of the two pieces of material, said gage being located above the 115 face of one of the pieces in position to engage an edge of the other, and means for feeding the work past the gage.

In testimony whereof I have signed my 120 name to this specification.

JAMES E. MCINTIRE.
